*N. S. Vedder.
Assignor to Wolfe & Warren.
Design for Cook Stove.*

Patented Jan'y. 27, 1851.

Dec. 826

A. S. Wedder, of Troy, N.Y.
Assoc^r to
Wolfs^r Warren, of Troy, N.Y.
Letters Patent No. 866. Dated Jan^r 27th 1857.

The Schedule referred to in these Letters Patent and making part of the same.

To all whom it may concern.

Be it known that I, A. S. Wedder of Troy, County of Rensselaer and State of New York, have invented or produced a new and original design for a Cook Stove, which I call the "Champion" and I do hereby declare that the following is a full and exact description of the same, reference being had to the annexed perspective drawings of the stove, and forming a part of this specification.

The description of my stove design is as follows. A is the top plate, with the ornamental moulding (a), B is the upper front plate, C,C, are front doors, decorated upon their panels with the rosettes (b,b) and checkered surface (c). D is the hearth plate with the ornamental moulding (d) and notched moulding (e). E is the lower front plate, with raised panel F, decorated with rosette (f) and checkered surface (g). G is the jamb plate, with fire door H, decorated with rosette (h) and checkered surface (i), the door frame being the moulding (j). I,I, are oven doors, decorated

with needles (k, k) and checkered surface (l, l), (m, m) are mouldings forming their frames, (n, n) are ornaments disposed on the panel surface of the jamb. T is the bottom plate with ornamental moulding (o). K is a leg with ornamental face (p).

Having described my design for cook stove, what I claim as new therein, is the ornamental design and configuration of Cook Stove plates, such as herein described and shown in the annexed drawing.

Witnesses.
